UNITED STATES PATENT OFFICE.

ROBERT J. COSSEBOOM, OF LEADVILLE, COLORADO, ASSIGNOR OF ONE-HALF TO LEONARD M. SMITH, OF LEADVILLE, COLORADO.

WRENCH.

SPECIFICATION forming part of Letters Patent No. 707,391, dated August 19, 1902.

Application filed March 29, 1902. Serial No. 100,544. (No model.)

To all whom it may concern:

Be it known that I, ROBERT J. COSSEBOOM, a citizen of the United States, and a resident of Leadville, in the county of Lake and State 5 of Colorado, have invented a new and Improved Wrench, of which the following is a full, clear, and exact description.

This invention relates to a class of wrenches having a fixed jaw and a sliding jaw, and has 10 for its object to provide a wrench of the class indicated with novel details of construction which adapt the wrench for quick and reliable adjustment, permit parts of the wrench to have a wide gripping range, and render 15 the wrench particularly well adapted to grip and turn pipes and bolt-bodies of small or large diameters and to be available where the space is cramped in which to operate the wrench.

20 The invention consists in the novel construction and combination of parts, as is hereinafter described, and defined in the appended claims.

Reference is to be had to the accompanying 25 drawings, forming a part of this specification, in which similar characters of reference indicate corresponding parts in all the figures.

Figure 1 is a side view of working parts of 30 the improved wrench. Fig. 2 is a partly-sectional side view of the same. Fig. 3 is a plan view of a portion of the wrench seen opposite the arrow *x* in Fig. 1. Fig. 4 is a transverse sectional view substantially on the line 4-4 in Fig. 2, and Fig. 5 is an enlarged detached 35 perspective view of a clamping device which is a novel detail of construction employed.

The lever-bar 10 in completed form is of sufficient length for effective service, and upon its forward portion two housing-plates 40 11 are oppositely secured near their rear ends by the rivets 12, so that main portions of the plates that project in advance of the front end of the lever-bar are held spaced apart thereon for reception and support of other 45 details of construction. The forward ends of the housing-plates 11 are preferably formed integral with a wrench-jaw 13, that projects forward and downward, having its upper surface serrated and rendered convex, as shown 50 in Figs. 1 and 2.

A wedge-block 14, which is an essential

feature of the invention, comprises an elongated body-piece longitudinally slotted, as at *a*, and having formed on the thinnest end a fulcrum-box 14^a, the edge wall of which is 55 preferably convexed, while the top surface thereof is disposed in the same plane with that of the wedge-body, this side of the latter being seated upon the flat lower surface of the lever-bar 10 when the parts of the wrench 60 are assembled. The wedge-block slopes forwardly on its lower side and is adjustably held upon the lever-bar 10 by the clamping-block 15, that tapers oppositely from the taper of the wedge-block and is provided with 65 two spaced studs *b*. The portions of the studs *b* that occupy the slot *a* in the wedge-block 14 are preferably squared in their bodies, having two opposite sides on each 70 adapted to loosely contact with the side walls 75 of the slot *a*, whereby the clamping-block 15 is prevented from lateral displacement. In the lever-bar 10 two spaced sockets *c* are formed for reception of the ends *b'* of the studs *b*, said portions being rounded so as to 80 adapt them to enter and fit said sockets, as shown in Figs. 2 and 4, this engagement of the studs serving to hold the clamping-block 85 15 in position on the lever-bar.

The clamping-block 15 is clamped upon the wedge-block 14 by the screw-bolt 16, that loosely passes through a perforation in the clamping-block between the studs *b* and screws into a tapped socket-hole *d*, formed in the lever-bar 10 between the socket *c*. Preferably the screw-bolt 16 is formed with a winged head 16^a, that contacts with a washer 17, imposed upon the clamping-block 15, so that the bolt by manual adjustment may press the clamping-block 15 upon the wedge-block 90 14 and bind the latter immovably upon the lever-bar 10, so as to prevent a forward sliding movement of the wedge-block.

In the space between the housing-plates 11 the tongue extension 18^a of the upper jaw 18 is 95 loosely inserted, said extension having parallel sides that loosely contact with the inner surface of the housing-plates and likewise with the sides of the fulcrum-box 14^a, into which the tongue extension projects and is 100 rockably held by the transverse pivot-bolt 19. The head portion of the jaw 18, having greater

thickness than the tongue extension 18^a, seats at each side of the latter upon the upper edges of the housing-plates 11, and from the seating-shoulders *e* curves forward and downward. The lower concave edge of the jaw 18, that overhangs the convex top surface of the lower jaw 13, is serrated to correspond with the teeth in the latter, so that these toothed faces may be adjusted in close proximity by 10 rocking movement of the upper jaw, as indicated in Fig. 2.

As shown in Figs. 2 and 3 at *g*, a plate-spring 20 is held by one end bedded in the front end of the lever-bar 10 and projects upwardly and forwardly, so as to press the upper jaw 18 downward, the resilience of the spring permitting the jaw 18 to be diverged from the stationary jaw 13 when this is necessary and as represented in Fig. 1.

20 In adjusting the wrench to take hold of a pipe or bolt the diameter of which is within the capacity of the implement the jaw 18 may be quickly diverged a proper degree from the fixed jaw 13, as indicated in Fig. 1.

25 simply by slackening the screw-bolt 16, which will release the pressure of the clamping-block 15 on the wedge-block 14 and permit the forward sliding movement of the wedge-block to be effected by manual pressure. As 30 the wedge-block moves forward the tongue extension 18^a of the upper jaw 18 will be correspondingly advanced, so that its front edge will impinge on the shoulder *f*, that defines the front wall of the space between the housing-plates 11, and a continuation of forward 35 sliding movement will obviously rock the jaw upward and rearward against stress of the spring 20 for the gripping engagement of the jaws upon a bolt or pipe A, held engaged

40 therewith by the force of the spring. The operator now turns the bolt 16, so as to enforce contact of the clamping-block 15 upon the wedge-block 14, and, as before mentioned, the clamping-block having its engaged side 45 inclined oppositely from the inclination of the wedge-block will be adapted to prevent the slightest rearward movement of the wedge-block when the jaws 13 and 18 are gripped upon a bolt or pipe body, and the lever-bar 10 is moved laterally to turn the bolt or pipe.

It will be seen that the improved wrench 55 may be applied to pipe or bolts that are close to vertical walls or corners which obstruct the use of ordinary wrenches and may be worked in small space. It will take hold of a small wire rod or a pipe or bolt of considerable diameter and turn either without injury thereto. Its range of adjustment is 60 large, and the working parts may be instantly moved and secured at any point within the range of the jaw 18.

It will be seen that by the novel construction and combination with the wedge-block 65 14, clamping-block 15, rockable upper jaw 18, spring 20, that bears upon the latter, and the handle-lever 10 a spreading adjustment of the

jaw 18 may be effected by a slight pressure upon the rear end of the wedge-block 14, if the bolt 16 is slackened just enough to permit the wedge-block to slide forwardly, the movable jaw 18 being rocked automatically into engagement with an object placed between the jaws by the spring 20. By employment of the counteracting wedge-blocks 75 14 and 15 a closer gripping adjustment can be made than when teeth are introduced between the lever-bar and movable jaw, as is common to this class of wrenches, and it will be manifest that the greater the resistance to 80 turning of the wrench when in use the tighter the upper jaw will be held against relaxing, and that without regard to the frictional contact enforced by the screw-bolt 16 and clamping-block 15 a reverse movement of the 85 screw-bolt may be readily effected and the wrench-jaws be detached from the object gripped instantly, as may be desired.

Having fully described my invention, I claim as new and desire to secure by Letters 90 Patent—

1. The combination with a lever-bar having a fixed jaw on one end, of a loose jaw, a wedge-block held to slide on the lever-bar and pivoted near one end upon an extension 95 of the loose jaw, and means for holding the wedge-block releasably clamped upon the lever-bar.

2. The combination with a lever-bar having a fixed jaw on one end, of a loose jaw having 100 an extension rockable in a slot in the lever-bar, a wedge-block held to slide on the lever-bar and pivoted near one end upon the extension of the loose jaw, and means for releasably clamping the wedge-block upon the 105 lever-bar.

3. The combination with a lever-bar having a convex-faced jaw on one end, and a loose jaw rockable in a slot in the lever-bar and having a concave face, of a slotted wedge-block bearing upon the lower edge of the lever-bar, a clamping-block having members 110 engaging the lever-bar, and a screw-bolt passing through the clamping-block and slot in the wedge-block, its inner end screwing into 115 the lever-bar.

4. The combination with a lever-bar having a convex-faced jaw on one end, and a loose jaw rockable in a slot in the lever-bar and having a concave face, of a slotted wedge-block, a fulcrum-box on one end of the wedge-block wherein one end of the convex-faced 120 jaw is pivoted, and a clamping-block the top face of which is inclined oppositely from the inclined surface of the wedge-block upon 125 which it bears, and a screw-bolt passing through the clamping-block and through the slot in the wedge-block and having screwed engagement with the lever-bar.

5. In a wrench of the character described, 130 the combination with the lever-bar having a fixed jaw on one end, and a mating rockable jaw, of a wedge-block slidable on an edge of the lever-bar and having a longitudinal slot

therein, one end of the wedge-block being pivoted upon a depending end of the rockable jaw, and a clamping-block having two spaced studs passing loosely through the slot in the wedge-block and entering sockets in the lever-bar, and a screw-bolt having a winged head, the threaded body of said bolt passing loosely through the clamping-block and the slot in the wedge-block, its inner end screwing into a tapped hole in the lever-bar.

6. In a wrench of the character described, the combination with the lever-bar, and a fixed jaw and a rockable jaw, of a slotted wedge-block, a clamping-block having a bear-

ing-face inclined oppositely to the inclined 15 face of the wedge-block upon which it bears, studs on the clamping-block, holding the wedge-block and said clamping-block from lateral displacement on the lever-bar, and a screw-bolt passing through the clamping- 20 block and wedge-block into the lever-bar.

In testimony whereof I have signed my name to this specification in the presence of two subscribing witnesses.

ROBERT J. COSSEBOOM.
